PRECAST CONCRETE CATCH BASIN WITH
STREET CURB INLET

James V. Curnutte, San Antonio, Tex.

Application December 19, 1949, Serial No. 133,837

4 Claims. (Cl. 182—6)

1

This invention relates to a pre-cast catch basin for a storm sewer.

In laying storm sewers, one of the more expensive items is the erection of catch basins for collecting water from the curb and conveying it to the sewer pipe. Conventional catch basins are either constructed of brick by high salaried brick masons or of concrete poured into forms erected by high salaried carpenters. Construction of either type of catch basin is time consuming and expensive.

It is, therefore, a major object of this invention to provide a catch basin which may be erected in less time and more economically than conventional catch basins.

More particularly, an object of the invention is to provide a catch basin composed of pre-cast elements which may be assembled by unskilled labor at the same time that the storm sewer is laid. Another object is to provide a catch basin composed of pre-cast components which can be connected to a storm sewer pipe running in any direction with respect to the street.

In accordance with these objects, certain features of the invention reside in the shape and arrangement of pre-cast concrete elements forming an inlet and lid assembly for the catch basin. For example, an important feature of the invention is the shape of a pre-cast concrete collar section for the catch basin, which collar section includes a cylindrical portion with an upwardly projecting semi-cylindrical portion so the ends of the semi-cylindrical portion form vertical shoulders extending upwardly from the exposed semi-circular top surface of the cylindrical portion to the semi-circular top surface of the semi-cylindrical portion. Another feature of the invention resides in the shape of an inlet section having a main portion with inwardly extending arms all of which rest upon the lower step of the collar section, with the arms abutting the shoulders. A flat lid section rests upon the top surface of the semi-circular portion of the collar section and upon the top surfaces of the arms of the inlet section. This is accomplished by having the arms of a height corresponding to the height of the shoulders on the collar section. To permit the flow of water into the basin, the main portion of the inlet section is thinner than the arm portions and has a top surface sloping downwardly and inwardly.

Another important feature of the invention resides in the arrangement of a cylindrical catch basin to support on its top circular surface the bottom circular surface of the collar section, and

2

having a lateral opening in its side wall to accommodate a cylindrical sewer pipe. The cylindrical basin may be turned so its opening is properly directed toward the pipe. Then the basin with the pipe connected will support the collar section and the other parts properly positioned with respect to the adjoining street, gutter and curb.

Other objects and advantages of the invention will become apparent from the following specification taken in connection with the accompanying drawings wherein

Fig. 1 is a perspective view of the inlet and lid assembly for a catch basin embodying the invention in its preferred form;

Fig. 2 is a vertical section through a catch basin embodying the invention and including the inlet and lid assembly of Fig. 2; and

Fig. 3 is an exploded view showing in perspective the components forming the inlet and lid assembly of Fig. 1.

To support the catch basin, a flat base or slab 11 is provided at the bottom of an excavation a given distance below the street level. Upon this base 11 rests a cylindrical basin 12 having a lateral opening 13 for receiving a cylindrical section 14 of storm sewer pipe. The basin 12 is formed of pre-cast concrete so it may be positioned on base 11 with its opening 13 facing any direction according to the direction in which pipe 14 is to be connected. The pipe 14 may be secured in the opening 13 by a thin layer of mortar 15.

Pre-cast cylindrical basin 12 has a circular top surface 16 upon which rests circular bottom surface 17 of cylindrical portion 18 of pre-cast concrete collar section 19. Collar section 19 has a semi-circular portion 21 extending upwardly from cylindrical portion 18. Exposed ends of semi-cylindrical portion 21 form shoulders 22 and 23 extending vertically from top semi-circular surface 24 exposed on cylindrical section 18 to top semi-circular surface 25 on semi-cylindrical portion 21. Collar section 19 is preferably of the same diameter as basin 12 and is arranged coaxially therewith. With this arrangement, collar section 19 may be positioned with its shoulders 22 and 23 parallel to the curb regardless of the position of basin 12 to have opening 13 accommodate the sewer pipe 14. A layer of mortar 26 may be interposed between top surface 16 of the basin 12 and bottom surface 17 of cylindrical portion 18.

This structure of the collar section 19 provides a stepped top surface, the lower step being

formed by semi-circular top surface 24 of the cylindrical portion 18, and the upper step being formed by semi-circular top surface 25 of the semi-cylindrical portion 21.

Supported on the lower step is a pre-cast inlet section 27 having a main portion 28 with inwardly extending arm portions 29 and 31. The bottom surfaces of the main portion 28 and the arm portions 29 and 31 are flush so they all rest on semi-circular top surface 24 of the cylindrical portion 18. End surfaces 32 and 33 of the arm portions 29 and 31 engage shoulders 22 and 23, respectively. A layer of mortar 34 may be interposed between the inlet section 28 and the collar section 19.

To provide a smooth surface for supporting lid section 35, arm portions 29 and 31 are of substantially the same height as shoulders 22 and 23 so that the top surfaces of the arm portions are substantially flush with the semi-circular top surface 25 of the semi-cylindrical portion 21. Main portion 28 of the inlet section 27 is thinner than the arm portions 29 and 31 and has its top surface 37 sloping downwardly and inwardly so water will drain across main portion 28 of the inlet section beneath lid 35 and into the basin 12. Inlet section 27 preferably has its main section 28 shaped to correspond to the shape of the curb so it will merge with portions of the curb on each side. To insure a proper joint between inlet section 27 and adjoining portions of the curb, metal reinforcing rods 38, 38, may project from opposite ends of the inlet section 27 so they will be in place when adjoining sections of the gutter and curb are constructed. Concave arcuate surfaces 39 and 41 are provided from main portion 28 to the top surfaces of arm portions 29 and 31 forming a smooth surface merging with adjoining curb sections. If desired, tapered transition sections (not shown) of curb may be connected on each side of the inlet section 27. These may also be pre-cast and provided with holes to receive rods 38.

Lid 35 rests on the top surface 25 of semi-cylindrical section 21 and on the top surfaces of arm portions 29 and 31 where it may be secured by a thin layer of mortar 43. Top section 35 may include suitable reinforcing rods 44 and a man-hole cover ring 45 providing access to the catch basin. At the curb side of the lid 35, its edge 46 is rounded to merge with concave arcuate surfaces 39 and 41 on the inlet section 27.

In assembling the catch basin of this invention, slab 11 is first provided at the base of an excavation. Then, basin section 12 is placed on the slab 11. Aperture or opening 13 in the wall of the basin 12 is faced in the direction of the storm sewer connecting pipe 14 and the connecting pipe may be secured in place by a thin layer of mortar. Next, the layer of mortar is placed on the circular top surface of the cylindrical basin 12 and collar section 19 is placed in position to rest upon the basin 12 so that its shoulders 22 and 23 are parallel to the gutter of the adjoining street. Then, inlet section is placed and mortared on the lower step of the collar section with its arm portions abutting shoulders 22 and 23. Finally, lid 35 is fitted onto the top of the collar section and the arm portions.

The component parts of the catch basin may be cast either at the site of construction or at a centrally located plant. The four pre-cast component parts are so shaped that they may be readily fitted together and placed by unskilled labor at the same time that the storm sewer is laid. In accordance with the invention, the com-

ponent parts, when properly assembled, are entirely self supporting. Thus, the catch basin may be constructed at the same time as the storm sewer is laid. Also, the catch basin may be constructed by the same crew that constructs the storm sewer, eliminating the necessity of employing specially skilled labor.

What is claimed is:

1. In a catch basin for a storm sewer, a pre-cast concrete inlet and lid assembly comprising a pre-cast concrete collar section including a cylindrical lower portion with its circular bottom surface adapted to rest upon a cylindrical catch basin and an integral semi-cylindrical upper portion with its exposed ends forming vertical shoulders extending upwardly from the exposed semi-circular top surface of said cylindrical portion to the semi-circular top surface of said semi-cylindrical portion, a pre-cast concrete inlet section including a main portion and integral arm portions extending inwardly from said main portion into engagement with said shoulders, the bottom surfaces of said arm portions being flush with the bottom surface of said main portion with each portion of said inlet section resting upon the semi-circular top surface of said cylindrical portion, the height of said arm portions corresponding to the height of said shoulders so that the top surfaces of said arm portions form continuations of the semi-circular top surface of said semi-cylindrical portion, said main portion of said inlet section being thinner than said arm portions and having its top surface sloping downwardly and inwardly, and a flat lid section resting upon the top surfaces of said semi-cylindrical portion and said arm portions.

2. In a catch basin for a storm sewer, a pre-cast concrete inlet and lid assembly comprising a pre-cast concrete collar section including a cylindrical lower portion with its circular bottom surface adapted to rest upon a cylindrical catch basin and an integral semi-cylindrical upper portion with its exposed ends forming vertical shoulders extending upwardly from the exposed semi-circular top surface of said cylindrical portion to the semi-circular top surface of said semi-cylindrical portion, a pre-cast concrete inlet section including a main portion and integral arm portions extending inwardly from said main portion into engagement with said shoulders, the bottom surfaces of said arm portions being flush with the bottom surface of said main portion with each portion of said inlet section resting upon the semi-circular top surface of said cylindrical portion, the height of said arm portions corresponding to the height of said shoulders so that the top surfaces of said arm portions form continuations of the semi-circular top surface of said semi-cylindrical portion, said main portion of said inlet section being thinner than said arm portions and having its top surface sloping downwardly and inwardly, and a flat lid section resting upon the top surfaces of said semi-cylindrical portion and said arm portions, said inlet section having concave arcuate surfaces extending from the top surface of said main portion to the top surfaces of said arm portions, said lid having a rounded edge merging with said arcuate concave surfaces.

3. A catch basin for a storm sewer comprising a cylindrical pre-cast concrete basin adapted to stand on end on a flat base and having its wall formed with a lateral opening to receive a cylindrical sewer pipe, a pre-cast concrete collar section including a cylindrical lower portion having

its circular bottom surface resting upon the circular top surface of said basin and an integral semi-cylindrical upper portion having its exposed ends providing vertical shoulders extending upwardly from the exposed semi-circular top surface of said cylindrical portion to the semi-circular top surface of said semi-cylindrical portion, a pre-cast concrete inlet section including a main portion and integral arm portions extending inwardly from said main portion into engagement with said shoulders, the bottom surfaces of said arm portions being flush with the bottom surface of said main portion with each portion of said inlet section resting upon the semi-circular top surface of said cylindrical portion, the height of said arm portions corresponding to the height of said shoulders so that the top surfaces of said arm portions are flush with the semi-circular top surface of said semi-cylindrical portion, said main portion of said inlet section being thinner than said arm portions and having its top surface sloping downwardly and inwardly, and a flat lid section resting upon the top surfaces of said semi-cylindrical portion and said arm portions.

4. A catch basin for a storm sewer comprising a cylindrical pre-cast concrete basin adapted to stand on end on a flat base and having its wall formed with a lateral opening to receive a cylindrical sewer pipe, a pre-cast concrete collar section including a cylindrical lower portion having its circular bottom surface resting upon the circular top surface of said basin and an integral

semi-cylindrical upper portion having its exposed ends providing vertical shoulders extending upwardly from the exposed semi-circular top surface of said cylindrical portion to the semi-circular top surface of said semi-cylindrical portion, a pre-cast concrete inlet section including a main portion and integral arm portions extending inwardly from said main portion into engagement with said shoulders, the bottom surfaces of said arm portions being flush with the bottom surface of said main portion with each portion of said inlet section resting upon the semi-circular top surface of said cylindrical portion, the height of said arm portions corresponding to the height of said shoulders so that the top surfaces of said arm portions are flush with the semi-circular top surface of said semi-cylindrical portion, said main portion of said inlet section being thinner than said arm portions and having its top surface sloping downwardly and inwardly, and a flat lid section resting upon the top surfaces of said semi-cylindrical portion and said arm portions, said inlet section having concave arcuate surfaces extending from the top surface of said main portion to the top surfaces of said arm portions, said lid having a rounded edge merging with said arcuate concave surfaces.
